UNITED STATES PATENT OFFICE.

FRANK J. DYETT, OF NEWARK, NEW JERSEY.

CONNECTING-ROD FOR TYPE-WRITERS.

SPECIFICATION forming part of Letters Patent No. 635,306, dated October 24, 1899.

Application filed July 14, 1898. Serial No. 685,939. (No model.)

To all whom it may concern:

Be it known that I, FRANK J. DYETT, a citizen of the United States, residing at Newark, in the county of Essex and State of New Jersey, have invented certain new and useful Improvements in Connecting-Rods for Type-Writers; and I do hereby declare the following to be a full, clear, and exact description of the invention, such as will enable others skilled in the art to which it appertains to make and use the same.

This invention relates to an improvement in rods for connecting the key-levers and type-bars of type-writers and similar machines.

15 The object of the invention is to employ a minimum amount of metal, to provide a rod of one continuous piece of metal, and to provide means for retaining the rod in position in the eye of the type-bar.

20 My invention consists in the novel construction and combination of parts hereinafter described and claimed, and illustrated in the accompanying drawings, in which—

Figure 1 is a perspective view of the connecting-rod attached to a section of a type-bar. Fig. 2 is a front elevation of the rod. Figs. 3 and 4 are side elevations. Fig. 5 is a vertical transverse section through the upper portion of the device on line 5-5 of Fig. 2. 30 Fig. 6 is a view of the spring and rod detached. Fig. 7 is a lower end view of said spring, and Fig. 8 is a view of the spring-blank.

Referring to said figures by letters of reference, A' is the threaded end of the rod A and is preferably of greater diameter than the remainder of the rod, which is diminished in diameter from a point above the thread, so as to reduce the quantity of metal in the rod, and 40 thereby reduce the weight thereof. At a desired point B near the upper end of the device the rod is bent back at a slight angle and then forward again into a hook C, which is preferably curved downwardly at the extreme end, as shown at c in the drawings. The center of the hooked end C is located directly above the straight intermediate portion of the rod A, so as to permit a direct pull thereupon.

50 Although the end c tends to hold the type-bar in the center of the hook C at all times, I provide means for retaining the same in posi-

tion which are extremely simple, though effective. This consists of a strip of preferably thin sheet-steel cut out in substantially the 55 shape shown in Fig. 8. The edges of the lower portion d thereof are turned up, making the same approximately arc-shaped in cross-section. This portion d is sprung over or clamped upon the rod A at and below the 60 point B, clasping the same tightly, as is obvious. The upper flat part D, which tapers slightly toward the end, bears normally against the end of hook C. In order to prevent the spring D from slipping upon the rod 65 A, it is preferably soldered thereto, although it could be attached equally as well in other ways, as by indenting the same.

The connecting-rod is readily attached to the type-bar by pressing back spring D and 70 inserting hook C into the eye of the type-bar. Upon removing pressure the spring will immediately spring back against the hook and retain the bar in its proper position. The downwardly-curved end c of the hook guides 75 the type-bar to the center of said hook, which is at a point directly over said bar, and as a result a direct downward pull in a line with the longitudinal axis of said rod is obtained.

As the rod is of but one piece from key-lever to type-bar, no trouble will result from the disconnection of parts resulting from the joints becoming loose, and as no strain is exerted upon the spring D, excepting while attaching or detaching the device, the stability 80 of the device will be readily appreciated.

In the foregoing description I have shown the preferred form of my invention; but I do not limit myself thereto, as I am aware that modifications may be made therein without 90 departing from the spirit or sacrificing the advantages thereof, and I therefore reserve the right to make such changes as fairly fall within the scope of my invention.

Having thus described my invention, what 95 I therefore claim as new, and desire to secure by Letters Patent thereon, is—

1. A connecting-rod for type-writers, consisting of a rod, a recurved hook formed at one end of said rod, the center of said hook 100 being directly above the intermediate portion of the rod, and a spring-strip having its inner end portion substantially arc-shaped in cross-section and clasping, and rigidly secured

to, said rod, its other end portion normally resting against the end of said hook, substantially as described.

2. A connecting-rod for type-writers, consisting of a rod having one end and its intermediate portion reduced, a recurved hook formed at the reduced end of said rod, the center of said hook being directly above the intermediate portion of the rod, and a spring-strip 10 having its inner end portion substantially arc-shaped in cross-section and clasping, and rigidly secured to, said rod, its other end portion normally resting against the end of said hook, substantially as described.

15 3. A connecting-rod for type-writers, consisting of a rod, a reduced intermediate and end portion, an inwardly-curved hook formed by the reduced end of said rod, the center of said curve being on a line with the intermediate portion of the rod, and a spring-strip 20 rigidly secured to said rod and having one

end portion normally bearing against the end of said hook.

4. A connecting-rod for type-writers, consisting of a rod, a reduced intermediate and end portion, an inwardly-curved hook formed by the reduced end of said rod the center of said curve being on a line with the intermediate portion of the rod, and a spring-strip 25 struck up from a single blank, having its inner end portion substantially arc-shaped in cross-section and clasping, and rigidly secured to, said rod, its other end portion normally resting against the end of said hook, substantially as described.

In testimony whereof I affix my signature in presence of two witnesses.

FRANK J. DYETT.

Witnesses:

JOHN H. MACKEY,
OSCAR OLSON.
